(57) **CLAIM**

The ornamental design for a printer, as shown and described.

DESCRIPTION

FIG. 1 is a perspective view of a printer showing my new design;
FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof;

FIG. 9 is an enlarged detail view of the encircled portion 9 of FIG. 1;

FIG. 10 is an enlarged detail view of the encircled portion 10 of FIG. 8;

FIG. 11 is an enlarged detail view of the encircled portion 11 of FIG. 8; and,

FIG. 12 is an enlarged side view thereof, shown in an environmental usage condition with a printout releasing therefrom.

The evenly broken lines are shown for the purpose of illustrating parts of the printer that form no part of the claimed design. The dot-dash broken lines in FIG. 9 are shown for the purpose of illustrating environmental subject matter that forms no part of the claimed design. The dot-dot-dash broken lines represent enlargement view designations on FIGS. 1, 8, 9, 10 and 11 form no part of the claimed design.

1 Claim, 11 Drawing Sheets
